UNITED STATES PATENT OFFICE.

CLINTON HORACE HULBERT, OF MANILA, PHILIPPINE ISLANDS.

INSTRUMENT FOR REPRODUCING AND MAGNIFYING SOUND-WAVES.

1,153,431.

Specification of Letters Patent. Patented Sept. 14, 1915.

Application filed January 15, 1914. Serial No. 812,298.

To all whom it may concern:

Be it known that I, CLINTON HORACE HULBERT, a citizen of the United States, residing at Manila, Philippine Islands, have invented new and useful Improvements in Instruments for Reproducing and Magnifying Sound-Waves, of which the following is a specification.

The object of my invention is a device, for producing, reproducing or magnifying speech or any other tone.

In the drawings:—Figure 1 is a vertical sectional view of the instrument on the line A A, Fig. 2; Fig. 2 is a top plan view of the instrument, the cover being removed; Fig. 3 is a perspective view of the instrument; Fig. 4 is a detail sectional view showing the drums used in multiple; Fig. 5 is a plan view of another embodiment of my invention; Fig. 6 is a longitudinal sectional view of a telephone receiver embodying my invention; Fig. 7 is a similar view of a telephone receiver showing a still further embodiment of my invention.

The reference numeral 1 represents the main body of the case which is preferably made of bronze or other non-magnetic metal having a cover 2 on which is secured the cap 3, there being a rubber gasket 4 between the cap and cover, said cap and cover being of bronze or other non-magnetic metal. The cover 2 is supported on a suitable insulation 4^a which in turn is secured on a lug 5 within the casing. The casing is supported on feet 6 having soft rubber cushions 7. Soft rubber gaskets 8 are secured on the upper side of the feet to insulate the screws which pass therethrough, thereby materially lessening the liability of outside sounds passing into the casing. Peep holes 9 are constructed in two sides of the casing, said holes being covered with glass. A cap 3^a similar to cap 3 is secured on the bottom of the casing over a rubber gasket 4^b. The cover 2 and the bottom of the casing is provided with an opening having lugs 10 and 11 on opposite sides thereof, a pole 12 composed of laminated sheet iron being secured at its outer end between the lugs 10 by means of a bolt 13 which passes through slot 14 in said pole. Insulation 15 is interposed between the lugs 10 and the pole 12. The lower pole 16 is of the same construction as the pole 12 and is secured between the lugs 11 by means of the bolt 17.

18 are insulations.

Upper and lower bobbins 19 and 20 having respectively, suitable insulation 21 are wound to form magnets 22 and 23. Four permanent magnets 24, 25, 26 and 27 are disposed in the case at right angles to each other around the pole 16, the bobbins extending between the arms of the magnets. Each permanent magnet is held in place by means of brass screws 28 which pass through the outside member of the bobbins 19 and 20 as shown in Fig. 1, thereby supporting the bobbins from the casing. The bobbins may be adjusted relatively by means of these screws as will be readily understood from Fig. 1.

The suitably shaped cell 29 of the instrument is composed of two very thin metallic diaphragms, forming opposite walls, capable of vibration, the flat surfaces of which are brought close together but do not touch each other except at their perimeter where they are clamped together, or better still soldered together, except at two points where openings are left to permit of the passage of air gas or liquid waves. In the construction of the cell it is absolutely essential that the metal be smooth and true. For sensitive work very thin metal must be used, while for heavy and loud tones correspondingly heavier metal may be used. The most satisfactory results that I have obtained were from a cylindrical cell four inches in diameter, with diaphragms 1/150 inch in thickness, separated about 1/16 inch. On increasing the size of the cell, the metal must be thicker in proportion to the width. I have obtained the best results when the diaphragms of the cell are the same distance apart as the poles are adjusted on the outside. The strain is then evenly divided and the thin diaphragms lie in a neutral point; therefore the strong magnets do not tend to cause the cell to bulge. The cell gives double tone waves as both diaphragms vibrate to and fro making a double compression and expansion, which action causes the air to rush in and out. If a combustible gas is passed through the cell to a lighted burner the flame clearly records variations in currents and tones. When the cell is filled with liquid and the openings restricted to that of a small glass tube, variations in reduced currents in the instrument are visible. When electric currents enter in one direction 110

in the magnet coil, the cell expands and on reversing the polarity the cell compresses. Alternating currents give a maximum vibration in the cell. Practice enables one to detect when the current is reversed. To obtain the best results the poles 16 should be adjusted as close as possible to the cell without touching it. Lock nutted brass screws 30 are secured to the perimeter of the bobbins 19 and 20 for holding and centering the cell 29 midway between the bobbins.

31 are fiber washers secured to the screws 30 which bear on the cell.

Two outlets 32 are secured in the peripheral openings of the drum 29 to which are connected rubber tubes 33, the other end of said tubes being connected respectively to the tubes 34 and 35. 36 and 37 are caps for said tubes secured to the casing by means of chains 38. The caps are to be screwed on when the instrument is not in use. When only one side of the instrument is in use the other side should be capped.

39 and 40 represent four binding posts, two for each coil or bobbin with conductors 41 and 42 so that each coil can be connected in series or in multiple.

When alternating currents are used, direct current electromagnets should be substituted for the permanent magnets, as the alternating current will demagnetize the permanent magnets. Multiple windings may be used in the type of instrument shown in Fig. 1 when it is desired for laboratory work. 35 Clear records are obtained from the coarse wire side when thermo-couples, for example, copper and iron, of a very weak voltage are used. When a circuit breaker is added either in series or in multiple with the junction to be tested, and the couple is heated by a flame, its raising and lowering of potential is audible and the stages when the current reverses are clearly distinguished in the difference in tone.

45 I have found that by filling the inside of the case with paraffin wax all exterior disturbing sound waves are cut out, but care must be taken to prevent the paraffin wax running in between the bobbins and the cell 50 and poles. To avoid this I fill in the wax in a pasty semi-liquid state. In addition the wax serves as insulation and makes the structure of the magnets more firm, thus reducing the spring and synchronizing with 55 the cell.

The cell is adapted and intended not only for use between the poles of a magnetic circuit, the poles of which are constructed of laminated sheet iron, annealed soft iron or 60 a bundle of soft iron wires, surrounded by magnet wire and charged by a permanent field or electromagnets, but also for separate or multiple use as shown in Fig. 4 wherein 39^a is a permanent magnet, 40^a the bobbin 65 with its magnet, 41^a the pole, 42^a and 43

the drums in multiple, and 44 are the connections for rubber tubes.

In Fig. 5 I have shown the drum connected through the tubes 33 to two ear pieces 46 having a spring 45 adapted to hold the ear 70 pieces in position in the ears.

In Fig. 6 I have shown my invention embodied in a telephone receiver. In this form the cell is not as sensitive as in Fig. 1 as the wiring and drum space are too small to get 75 full efficiency.

In Fig. 7 I have extended the pole pieces and the cell practically the full length of the telephone receiver.

When one of the openings 32 is plugged, 80 the cell may be used for open speech and tones. When both of the openings are open and connected with ear pieces, the cell may be used in connection with wireless and telephone receiving stations as a receiver. In 85 submarine signaling the thickness of the diaphragms should be proportionate to the depth to which the instrument is to be submerged. For the detection of sound and tone waves in the earth, volcanic disturbances, mine signaling, etc., the cell must be embedded in sand or earth or immersed in water in close contact with the earth. To detect the direction of the source of the sound waves, deaden one of the diaphragms 90 and face in different directions until the best results are obtained. The applicant has also discovered that the transverse membranous walls of his metallic cell will vibrate at a place between opposite magnetic 100 poles in response to externally induced currents, even when there is no intimate metallic connection either to the cell or the magnet or magnets, the poles of which directly influence it. A make or break in a current 105 from a battery, dynamo or other electrical source, through a loop of wire or an aerial conductor, removed from the instrument and not connected with it by metallic connections, can be recorded by the instrument 110 when the latter is properly placed.

What I claim is:—

1. In a device of the character described, a cell comprising two flexible diaphragms secured together throughout their perimeter with the exception of two opposite points, said diaphragms being placed apart a distance equal to a small fraction of the thickness of each diaphragm.

2. In a device of the character described, a cell comprising two flexible diaphragms, a wall joining said diaphragms together throughout their perimeter and two opposite ports formed in said wall, said diaphragms and said wall inclosing a chamber having a thickness, comparing with the thickness of each diaphragm approximately as 10 to 1.

3. In a device of the character described, a cell comprising two flexible diaphragms and a wall joining said diaphragms together 130

so as to form a flat cylindrical chamber between them, two opposite ports being formed in said wall, in combination with magnets on each side of said cell and magnetic poles between said magnets, the thickness of said chamber being approximately equal to the distance between each diaphragm and the nearest pole.

4. In a device of the character described, 10 a cell comprising two flexible diaphragms and a wall joining said diaphragms together so as to form a flat cylindrical chamber between them, two opposite ports being formed in said wall, in combination with permanent 15 magnets, pole pieces for said magnets and magnet coils disposed between the cell and said permanent magnets, the distance between said cell and each of said pole pieces being equal to the distance between said 20 diaphragms.

5. In a device of the character described, 25 a cell comprising two flexible diaphragms and an annular wall joining said diaphragms together throughout their perimeter, thus forming a thin cylindrical chamber within the cell, two opposite ports being formed in said wall, in combination with permanent magnets, pole pieces composed of laminated sheet iron for said magnets and 30 magnet coils disposed between the cell and said permanent magnets, said cell being situated between said pole pieces and means for adjusting said pole pieces relative to said cell, whereby the distance between the cell 35 and one of said pole pieces may be made equal to the thickness of said chamber.

6. In a device of the character described, 40 a cell comprising two flexible diaphragms and an annular wall joining said diaphragms together throughout their perimeter, leaving a narrow cylindrical space between them, two opposite ports being formed in said wall, in combination with magnetic coils disposed on opposite sides of 45 said cell and central cores forming opposite poles in said coils, means to center the cell between said coils, whereby the distance between each pole and the cell will be made

approximately equal to the thickness of said space.

7. In a device of the character described, 50 a cell having two flexible diaphragms with a narrow space between them, in combination with pole pieces situated on two opposite sides of said cell and externally there- 55 to, magnets grouped around said pole pieces, magnetic coils arranged on two opposite sides of said cell, means to center said cell with reference to said coils and means to adjust said coils and said poles axially relatively to said coil so that the distance between each pole and the cell becomes approximately equal to the thickness of said space.

8. An instrument for reproducing and 60 magnifying sound waves, comprising a cell having two flat, circular diaphragms fastened together around the periphery so as to form a sealed cylindrical chamber for a fluid, the thickness of said chamber compar- 70 ing with its diameter approximately as 1 to 64; a member having connection with said chamber for receiving fluid therefrom and transmitting its fluctuations.

9. An instrument for reproducing and 75 magnifying sound waves, comprising a cell having two flat, circular diaphragms fastened together around the periphery so as to form a sealed cylindrical chamber for a fluid, the thickness of said chamber compar- 80 ing with its diameter approximately as 1 to 64; a member having connection with said chamber for receiving fluid therefrom and transmitting its fluctuations, electromagnets on both sides of said cell provided with a 85 central pole on each side of the cell and a sound proof non-magnetic casing for said cell, magnets and poles.

The foregoing specification signed at Baguio, Mountain Province, P. I., this 23rd 90 day of May, 1913.

CLINTON HORACE HULBERT.
